CHAISE LONGUE

Harry H. Goldberg, Philadelphia, Pa., assignor to
Bunting Glider Company, Philadelphia, Pa., a
corporation of Pennsylvania

Application March 28, 1952, Serial No. 19,096

Term of patent 14 years

(Cl. D15—11)

To all whom it may concern:

Be it known that I, Harry H. Goldberg, a citizen of the United States and a resident of Philadelphia, county of Philadelphia, State of Pennsylvania, have invented a new, original, and ornamental Design for a Chaise Longue, of which the following is a specification, reference being had to the accompanying drawings, forming a part thereof, wherein:

Figure 1 is a perspective view of a chaise longue showing my new design;

Figure 2 is a side elevational view thereof;

Figure 3 is a front elevational view thereof as viewed from line 3—3 of Figure 2; and

Figure 4 is a rear elevational view thereof as viewed from line 4—4 of Figure 2.

The dominant and characteristic features of the design reside in the parts shown in full line in the drawings.

I claim:

The ornamental design for a chaise longue, substantially as shown and described.

HARRY H. GOLDBERG.
